UNITED STATES PATENT OFFICE

GEORGE FRED WALTER, OF MAPLEWOOD, NEW JERSEY, ASSIGNOR OF ONE-HALF TO
HARVEY P. SLEEPER, OF SHORT HILLS, NEW JERSEY

LIVE-WIRE DETECTOR

Application filed November 12, 1926. Serial No. 318,617.

My invention relates to a new and improved live-wire detector.

One of the objects of my invention is to provide simple, efficient and portable apparatus for use in power houses or the like, whereby the attendant can readily determine whether a bus bar or other detector is carrying an electric current.

Another object of my invention is to provide a device of this type which embodies a glow tube, such as a neon tube or the like, of improved form.

Another object of my invention is to provide a device of this type, in which the glow of the neon tube or similar glow tube device is readily visible.

Other objects of my invention will be set forth in the following description and drawing which illustrate a preferred embodiment thereof, it being understood that the above general statement of the objects of my invention is intended to merely generally explain the same, and not to limit it in any manner.

Fig. 1 is a side elevation showing the improved device.

Fig. 2 is a sectional view along the line 2—2 of Fig. 1.

Fig. 3 is a detail view showing the glow lamp and the mount therefor.

Fig. 4 is a sectional view on the line 4—4 of Fig. 2.

Fig. 5 is a detail view showing the front contact of the device.

Fig. 6 is a sectional view on the line 6—6 of Fig. 2.

It has heretofore been proposed to detect the presence of an electric current in a conductor, by using a glow tube, such as a neon tube or the like. However, such devices have hitherto not been so constructed as to make the glow of the tube readily visible, especially when the tube was held a considerable distance from the attendant.

According to my invention the glow tube N is connected to a planar base member 20, made of any suitable insulating material, by means of spring sockets 15 and 22. The spring socket 15, which releasably holds the adjacent metal contact end 14 of the glow

tube N, is connected to the base member 20 by means of a suitable fastening device 24. This socket 15 is made of any suitable springy metal.

The second socket 22 comprises a plurality of spring arms mounted upon a base which is connected by means of a suitable bolt and nut to a lateral base element 21, which is made of any suitable insulating material, and which is connected to the longitudinal base element 20 by means of a screw or other suitable fastening means.

As shown in Figs. 2 and 3 a condenser C is connected to the spring socket 22. This condenser C may consist of a sheet of copper or other suitable metal bent into cylindrical form, and having its ends separated. This condenser has the effect of increasing the capacity of the adjacent metal contact end of the glow tube N. The glow tube N has a laterally bent portion 11 by means of which the glow of the tube can be readily observed.

The upper end of the longitudinal base member 20 is connected to the reduced end 1a of a support member 1. As shown in Fig. 6 for example, the upper part of the supporting member 1 is semi-cylindrical. As shown in Fig. 4 the reduced upper end 1a of the supporting member 1 has a width which is only slightly greater than the width of the longitudinal base member 20. The supporting member 1 is also made of any suitable insulating material.

The supporting member 1 fits within a tube 4', also made of suitable insulating material which is provided with an opening at one side thereof.

A hood 4 is provided with a cylindrical surface which is connected to the tube 4' by means of fastening members 26. This hood 4 has a flared portion within which the laterally projecting portion 11 of the glow tube N extends.

A cap 7 is provided which is connected to the tube 4' by means of fastening members 30. The cap 7 is also made of insulating material and it is provided with a perforation through which the contact rod 5 extends. This contact rod 5 has a curved tip 8, which can be caused to contact with the bus bar B, 100

or any other conductor which is to be tested.

The cap 7 is provided with recesses S and S' so that it can only be placed within the tube 4' in predetermined position. Likewise, the recesses S and S' prevent the cap 7 from turning, by cooperating with members 20 and 1a.

A contact spring 6 is connected to the contact rod 5 by means of a nut 9, and a second nut 10 is used for holding the contact rod 5 to the cap 7.

When the parts are assembled the contact 6 touches the adjacent metal contact end 14 of the glow tube N.

The tube 1 is provided with a threaded extension 2, to which an extension stick 3 can be connected.

The operation of the device is as follows:

When the parts are assembled as previously described, a bus bar or the like is tested by applying the tip 8 of the contact rod 5 thereto. If an alternating current is passing through the said bus bar B, then the voltage of that portion of said bus bar B which is in contact with the tip 8 changes rapidly.

An alternating voltage is therefore impressed upon the tube end 14, which touches the contact spring 6. The alternating voltage of said metal end 14 induces a corresponding alternating voltage of opposite sign upon the other metal end of the tube. The two metal ends of the tube act like a condenser. Hence, if the upper metal end is given a positive charge, this induces a negative charge on the adjacent face of the opposite metal end, so that a discharge tends to pass through the adjacent surfaces of the metal ends. If the impressed voltage is sufficiently high a discharge current passes between the members 14, producing the familiar glow. This is facilitated by the fact that an ungrounded condenser C is employed, merely to increase the capacity of the adjacent end 14.

The hood 4 which is also made of suitable insulating material keeps light away from the lateral extension 11 of the glow tube, so that when this glows, it is readily visible.

I have shown a preferred embodiment of my invention, but it is clear that numerous changes and omissions could be made without departing from its spirit.

I claim:

1. A live-wire detector comprising a first tubular member made of insulating material having a cut-away and non-tubular extension, a second tubular member made of insulating material and having a cut-away and non-tubular extension connected to said first tubular member, to form a tubular casing having an opening at one side thereof, a hood fitting over said second tubular member and connected thereto, said hood extending over the opening in said casing and being open at one end thereof, a supporting strip located within said first tubular member and carrying

spaced supporting means adapted to engage and support the ends of a flow tube, and contact means connected to said tubular casing and adapted to contact with one of the ends of the glow tube.

2. A device according to claim 1 in which a condenser is connected to the supporting means which are spaced from said contact means.

3. An electrical test stick for detecting the presence of alternating current potentials comprising a housing, an exterior electrical terminal on said housing and adapted to be held at a point of alternating current potential, a neon tube having a luminous portion arranged angularly within said housing and having an electrode connected to said terminal, and a condenser plate contained within said housing, said neon tube having a second electrode connected to said condenser plate said condenser plate serving to increase the flow of electro-static current through said neon tube in use by virtue of the electro-static capacity between said condenser plate and the earth.

In testimony whereof I affix my signature.
GEORGE FRED WALTER.
